UNITED STATES PATENT OFFICE.

THORNTON F. SANBORN, OF NEW YORK, N. Y.

EVAPORATING APPARATUS.

1,116,927.

Specification of Letters Patent. Patented Nov. 10, 1914.

Application filed April 19, 1913. Serial No. 762,319.

To all whom it may concern:

Be it known that I, THORNTON F. SANBORN, a citizen of the United States, residing at New York, county of New York, and State of New York, have invented certain new and useful Improvements in Evaporating Apparatus, of which the following is a specification.

This invention relates to evaporating apparatus.

Vacuum sugar evaporating apparatus is usually, in practice, composed of two or more cells or "effects" through the cells of which the evaporating process is carried on in succession.

My object is to provide, first, an evaporating "effect" or cell of novel construction, whereby it is adapted for the addition of one or more cell or "effect" units for its enlargement to any desired extent to transform such coupled or combined units into a single cell or "effect," thus providing means whereby the size and capacity of a given cell or "effect" may be increased to any desired extent.

Another object is to provide in a multiple-cell or multiple-"effect" evaporating apparatus, cell or "effect" units to which other cell or "effect" units may be added from time to time to increase the capacity of the complete evaporator according to the required increase in its capacity.

A still further object is to provide, in an evaporating apparatus, self-contained cells or "effects" any or all of the individual cells or "effects" of which are adapted to have their individual capacity increased by the addition thereto of corresponding self-contained cells or "effects," whereby each cell or "effect" may have its individual capacity increased to any desired extent without interfering with the usual successive treatment of the material being evaporated by the respective cells.

A further object of the invention is the provision in an evaporating apparatus of cells or "effects" of such form, preferably polygonal, and preferably self-contained, that they may be interchangeably connected to enable the capacity of the apparatus to be indefinitely increased by increase of the capacity of the respective cells or "effects" without necessitating an increase in the number of cell or "effect" units

through which the evaporating process is to be carried on.

The present invention also has for its object the provision of means whereby any of the usual or standard types or constructions of evaporating cells or "effects" may be utilized for the indefinite increase of the capacity of the respective cells or "effects," however the evaporating process may be carried on within a particular cell or "effect," the present invention not being limited to application of cells or "effects" of the particular construction which appears hereinafter.

The invention has for its object, in respect to all of the foregoing objects thereof, the provision of means whereby the increase in capacity is a proportionate enlargement throughout the respective cells or "effects" so that the added quantities of vapor evolved, gases delivered and condensation produced are accommodated and taken care of proportionately and the enlarged capacity of a given cell or "effect" unit remains unchanged in the valves, pipe connections and operators required, as well as in every other respect.

Preferably, the various juice inlets and outlets, the drain line, the steam inlets, the noncondensable gas pipes, and other connections are made by means of common pipes so that all connections are under the same control and handled by the same valves and means as in the original evaporating apparatus before its capacity has been increased. Preferably, additional vapor pipes are employed for connection of the added or new cell units which are applied in carrying out the invention.

The invention consists in means and instrumentalities adapted to carry out and perform the foregoing objects, and others which will appear more fully hereinafter.

One embodiment of the invention is set forth fully hereinafter and shown in the accompanying drawings, in which—

Figure 1 is a side elevation; Fig. 2, a plan view; Fig. 3, an end elevation; Fig. 4, a vertical section through a cell or effect whose capacity has been doubled; and Fig. 5, a vertical section through a single or unitary cell.

The cells or effects 1 may be used singly or in any desired multiples, such as two,

four, six, eight, or even more, a quadruple effect being illustrated.

The drawings disclose cells or effects which are of the same self-contained construction and all similar, the interior construction being substantially that set forth in my patent on evaporating apparatus, No. 1028792, dated June 4, 1912, but the invention is not limited to cell units of the internal construction set forth in that patent and it may just as well be applied to any of the usual or standard types of evaporating cells and apparatus, and I do not limit myself to its application to cells of the construction set forth in my Patent No. 1028792.

The cell units, if constructed according to my Patent No. 1028792, which construction is illustrated, are provided with a calandria 5 formed by a bottom or tube sheet 2 to which are suitably secured heating tubes 4 which open into the calandria at 3, the bottom of the latter being shown at 6. Suitably secured to the bottom 6 is a plate 7 which provides a non-condensable gas chamber 8. Suitably secured to the bottom plate are the take-off tubes 13 for the non-condensable gases which tend to accumulate in the upper ends of the heating tubes 4, the tubes 13 being in communication with the interior of tubes 4 only at the upper ends of said tubes 13, as set forth in my Patent No. 1028792.

The juice outlet or take-off is shown at 10, the condensation water outlet appears at 11 and the chamber 8 has a gas take-off or outlet 12.

The invention is not restricted to a cell of the internal construction described and is applicable, as will presently appear, to any evaporator.

Where the initial installation is multiple, as is usually the case, the cell units 1 are connected by vapor pipes 17, the last one 45 17^a of which leads to the usual condenser 18, the remaining vapor pipes leading from the domes 1^a of a preceding cell to the calandria 5 of the next cell of the original installation.

50 As usual in evaporating apparatus, the juice in the first cell becomes heavier and is drawn by vacuum into the next cell through the pipe 10 and again leaves that cell through the correspondingly designated pipe 55 to pass to the following cell and so on, the finished product being pumped from the last cell of the series. The vapor passes from cell to cell and finally into the condenser 18.

If the interior construction of the cells is like that set forth in my Patent No. 1028792, the non-condensable gases pass out through outlets 12 into the calandria 5 of the succeeding cell for the utilization of the heat thereof, as set forth in said patent. Having initially installed a multiple effect evapo-

rator whether of a construction set forth in my Patent No. 1028792, or similar to any of the usual or standard multiple effect evaporators known to the art, if an increase in capacity of the plant is desired, it cannot, 70 as such evaporators are at present known to the art and constructed, be carried out under the same control and with a proportionate increase of capacity or without rebuilding the installation at very heavy expense. 75

The present invention provides for any desired enlargement or increase in the capacity of one or more cell units of an evaporator without multiplying the appliances necessary to the control thereof or over-crowding outlets and transfer pipes beyond their capacity but, on the other hand, contemplates an increase to any desired extent, in the individual cell capacity by the addition of one or more cell units to the initially installed cell units to thereby enlarge the capacity of any cell unit, or, all of those originally installed and at the same time to provide a proportionate increase in the vapor pipes, juice outlets, drainage outlets and, if constructed according to my Patent No. 1028792, the non-condensable gas outlets, without multiplying the number of valves required to control any part of the apparatus. 85 90 95

In carrying out the invention, each cell whose capacity is to be enlarged is coupled to another cell, preferably of the same shape and construction, the sides of the coupled cell units being previously removed and the cell units bolted or secured together so that the entire interior of one is in communication with the entire interior of the other which is coupled thereto, but each has its own dome, heating means, juice outlet, condensation outlet and, if constructed in accordance with my Patent No. 1028792, its own non-condensable gas outlet. That is to say, each cell unit is preferably self-contained and to eliminate multiplication of controlling valves and the like, when another cell unit is coupled to the first, the juice outlets are directly coupled, the respective condensation outlets are preferably coupled and if the cell is constructed according to my Patent No. 1028792, the outlets for the non-condensable gases are directly coupled. The vapor pipes are preferably separate as in usual practice, and each cell unit will be increased in capacity and the added cell units will have their vapor pipes arranged and interconnected the same as the cell units of the original installation. 110 115 120

In carrying out my invention, I preferably construct the cell units 1 with corresponding removable sides so that, as shown in Fig. 4, when another cell unit is coupled to one originally installed, the removable side of the former may be taken off and the two units bolted together and said side ap- 125 130

plied to the added cell unit, leaving the two cell units in complete interior communication.

Preferably, though not necessarily, the 5 cell units are of polygonal form and preferably square. Making them of polygonal form, preferably square, provides means whereby any side of one cell unit may be coupled to any side of another cell unit and, 10 being of the same construction, they are interchangeable and can be readily secured together. The polygonal construction of the cell units appears in Fig. 2.

Referring to Figs. 4 and 5, the removable 15 side 20 of the previously installed cell may, on the addition of another cell unit, be moved to the position shown at 20^a, Fig. 4, and the flanges 21 which are provided on all sides of a cell unit may be directly bolted 20 together, thereby placing the two cell units in complete interior communication, each cell unit being self-contained, but both forming, in effect, a single cell, although both have independent vapor pipes 17 and 25 independent domes 1^a, such construction affording a corresponding enlargement of vapor outlet or transfer as the cell is increased in capacity by the addition of the extra cell 30 unit thereto, the two units constituting a single cell. Similarly, a third, fourth, etc., cell unit may be added, the side 20^a being moved each time another cell unit is added so that a given cell unit 1 may have its 35 capacity doubled, trebled, quadrupled, etc. The initially installed cell unit 1 is provided with a removable side 22 having sight 40 glasses 23. It will be understood that the sides 20 and 22 are interchangeable and that the cell unit being multiple-sided, these sides may be changed about as desired.

I wish it understood that the enlargement 45 of the capacity of any given cell unit by the addition of one or more corresponding units thereto results in a proportionate enlargement or increase throughout and that added duty is not brought upon the initially installed outlets; all parts are proportionately increased in capacity. I also wish it understood that my invention is not merely the 50 duplication of the initially installed effect, but, on the contrary, the present invention provides for an increase in the capacity of each cell. The invention, therefore, as distinguished from the installation of duplicate apparatus, consists in increase in individual cell capacity to any desired extent, the system being one of units which may be added to form a part of the original cell construction and may be added to from time 55 to time as found necessary or desirable. The invention consists, further, in a cell of polygonal form, and still further, in one having interchangeable removable sides. The invention also consists, broadly, in the 60 provision of means whereby an evaporating apparatus

may be built with any desired cell capacity and at the same time proportionately increase all outlets and other parts which have a duty to perform in carrying 70 on the evaporating process.

While I have illustrated the invention as applied to vertical tube evaporators, it is just as applicable to horizontal tube evaporators. Furthermore, whereas I have shown the invention as having cells whose 75 interior construction is similar to that set forth in my Patent No. 1028792, it is not restricted to interior cell construction of that kind and it is just as adaptable to any of the ordinary or standard types of evaporators 80 heretofore and now known to the art.

I am aware that various modifications could be resorted to in carrying out my invention in the different aspects thereof, and I do not, therefore, limit myself to the specific constructions herein set forth and disclosed, but consider that my claims cover all modifications falling within the spirit and scope of the invention.

Having thus described my invention, what 90 I claim as new and desire to secure by Letters Patent, is:—

1. An evaporating cell unit whose vapor and juice containing parts are constructed and adapted for a proportionate increase or enlargement internally of the cell unit by the coupling thereto of another cell unit 95 with its vapor and juice containing parts in internal communication with the vapor and juice containing parts thereof.

2. An evaporating cell unit whose vapor and steam containing parts are constructed and adapted for a proportionate increase or enlargement internally of the cell unit by the coupling thereto of another cell unit 105 with its vapor and steam containing parts in internal communication with the vapor and steam containing parts thereof.

3. An evaporating cell unit whose steam and juice containing parts are constructed and adapted for a proportionate increase or enlargement internally of the cell unit by the coupling thereto of another cell unit with its steam and juice containing parts in 110 internal communication with the steam and juice containing parts thereof.

4. An evaporating cell unit whose vapor, juice and steam containing parts are constructed and adapted for a proportionate increase or enlargement internally of the cell unit by the coupling thereto of another cell unit with its vapor, juice and steam containing parts in internal communication with the vapor, juice and steam containing 120 parts thereof.

5. An evaporating cell of polygonal form having a plurality of its walls arranged in planes angularly disposed to each other and each adapted to be removed, thereby adapting different ones of its walls on its differ- 130

ent sides to be coupled to another cell for an increase of the individual capacity of the cell.

6. An evaporating cell unit having vapor, juice and steam containing parts and a removable wall which forms a side of said vapor, juice and steam containing parts.

7. In an evaporating apparatus, a plurality of cell-units adapted for conjointly and successively carrying on the evaporating process by conducting the vapor externally from cell to cell and, respectively, constructed and adapted for an increase in individual cell capacity by the coupling thereto of one or more additional cell-units in internal communication with the cell units aforesaid, without disturbing the original installation.

8. In an evaporating apparatus, a plurality of cell-units adapted for conjointly and successively carrying on the evaporat-

ing process by conducting the vapor externally from cell to cell, said cell-units being, respectively, provided with a removable side adapting them for an increase in individual cell capacity by the coupling thereto of one or more additional cell units in internal communication with the cell units aforesaid through their open sides.

9. A multiple-cell evaporating apparatus whose individual cells are constructed and adapted for individual enlargement and increase in capacity throughout by the coupling of one or more cell-units thereto and in internal communication therewith.

In testimony whereof, I hereunto affix my signature in presence of two witnesses.

THORNTON F. SANBORN.
